GUSTAF DALÉN, OF LIDINGÖN, STOCKHOLM, SWEDEN, ASSIGNOR TO SVENSKA AKTIEBOLAGET GASSACCUMULATOR, OF STOCKHOLM, SWEDEN.

SEARCH-LIGHT APPARATUS.

1,350,547.

Specification of Letters Patent. Patented Aug. 24, 1920.

Application filed January 23, 1917. Serial No. 143,948.

To all whom it may concern:

Be it known that I, GUSTAF DALÉN, engineer, residing at Skärsätra, Lidingön, Stockholm, Sweden, have invented certain new and useful Improvements in Search-Light Apparatus, of which the following is a specification.

The present invention refers to certain improvements in search light apparatus, in which the source of light is in the form of an incandescent body, heated by means of gas or an electric arc lamp or incandescent lamp. The invention has for its object means whereby the continued glowing of the source of light, after this latter has been extinguished, is obviated from being perceptible outside of the search light apparatus. This is an important condition especially when using search light for military purposes. The essential feature of the invention consists of a screening device, which automatically enters into action when the source of light is extinguished and lighted, in such a manner, that the source of light is automatically screened, when the source of light is extinguished, whereas the screening device or part of it automatically is displaced in such a position, when the source of light is lighted, that it intercepts the light rays reflected by the search light apparatus in the smallest possible degree. For this purpose the screening device or the movable part of it is operated by the fluid, such as gas or electricity, feeding the source of light. When gas is employed the screening device or the movable part of it preferably is operated by a diaphragm, exposed to the pressure of the gas employed, whereby the movement of the screening device in one direction may be effected by means of a spring if required.

The screening device preferably is arranged in such a manner, that it closely surrounds the source of light in its screening position, whereby the dimensions of the device are made small, and the movable part of the same is easily handled, and intercepts but very little light in the position occupied when the source of light is lighted.

On the accompanying drawing Figure 1 is a vertical section of one construction according to the invention, showing part of a search light apparatus, in which a movable part of the screening device is operated by

a gas actuated diaphragm. Fig. 2 is a horizontal section on line A—B in Fig. 1. Fig. 3 is a vertical section on line C—D in Fig. 1.

With reference to Figs. 1—3 1 indicates part of the casing of the search light apparatus, and 2 the reflector. As the source of light an incandescent body 3 is provided, which is heated by the flame of a gas burner 4. Gas or a gas mixture, such as oxy-acetylene gas, is fed to the burner 4 through the conduit 5 from a mixing chamber 6, to which the gases are introduced through channels 7, 8, in a standard 9 secured to the casing 1. The screening device according to the construction illustrated consists partly of a fixed screen 10, supported by the standard 9, and having mainly half cylindrical form, partly of a movable screen 11, also mainly of half cylindrical form and movable concentrically with and around the screen 10. It is supported by a movable sleeve 12, surrounding the standard 9. The sleeve 12 is automatically movable by means of a diaphragm 13, closing a casing 14, to which gas is introduced from the channel 8 through the channel 15. Any suitable transmission may be provided for transferring the movement of the diaphragm 13 to the screen 11 or to the sleeve 12, carrying the same. On the drawing said transmission consists of a gear segment 16 on the sleeve 12 and a gear segment 17 on an arm 18, secured to an oscillating shaft 19, connected with the diaphragm 13 by means of a bar 20 and an arm 21 on the shaft 19. The arrangement is such, that on introducing gas through the channel 8 for lighting the flame of the burner 4, gas simultaneously is introduced to the casing 14 and to the diaphragm 13, whereby the screen 11 is moved half a revolution, so that the casing, formed by the two screens 10 and 11 in closed position, is opened and the rays of light from the flame or the incandescent body 3 strike the reflector 2 for being parallelized by the same. When the flow of gas through the channel 8 is cut off, the screen 11 is moved back to its original position by the action of the spring 22, so that a practically closed casing is established by the two parts of the screening device.

The gas channels 7 and 8 are connected by means of flexible tubes 23, 24, with gas receivers, not shown on the drawing. Valves 25, 26 may be provided outside of the search

light apparatus, if required, at a distance from said apparatus, so that the screen can be handled from a distant place.

In the construction shown the holder 27 of the incandescent body 3 is fixed to the screen 10, which is movable on the bolt 28, so that the screen can be turned down for inspection or exchange of the incandescent body. The screen 11 is also movable by hand and can be secured in an open position against the action of the spring 22 by means of the screw 29.

In the construction shown the movable screen 11 is oscillating around the fixed screen 10.

Having thus described my invention, what I claim is:

1. A search light apparatus, comprising in combination a source of light, a screen device comprising a fixed member and a rotary member, a conduit for conveying an illuminating medium to said source of light, means for controlling the flow of illuminating medium, and means directly connected with said conduit and actuated by the illuminating medium flowing therein, for moving the rotary member out of screening position when said medium commences to flow and means for moving the rotary member back into screening position when the medium ceases to flow in said conduit, for the purpose set forth.

2. A search light apparatus, comprising in combination a source of light, a screen device comprising a fixed member and a rotary member, a conduit for conveying a supply of gas to the source of light, means for controlling the flow of gas, a diaphragm casing, in direct communication with said conduit, a diaphragm within said casing, and means connected with said diaphragm for moving the rotary member out of screening position when the gas commences to flow and means for moving the rotary member back into screening position when the gas ceases to flow in said conduit for the purpose set forth.

3. A search light apparatus, comprising in combination a source of light, a screen device comprising a fixed member and a rotary member forming together a hollow cylindrical casing, a conduit for conveying an illuminating medium to said source of light, means for controlling the flow of illuminating medium, means directly connected with said conduit and actuated by the medium flowing therein for moving the rotary mem-

ber out of screening position when the medium commences to flow and means for moving said rotary member back into screening position when the medium ceases to flow in said conduit, means for moving the rotary member by hand and means for locking said rotary member in its non-screening position.

4. A search light apparatus, comprising in combination a source of light, a screen device comprising a fixed member and a rotary member, a conduit for conveying a supply of gas to the source of light, means for controlling the flow of gas, a diaphragm casing in direct communication with said conduit, a diaphragm within said casing, a shaft oscillated by the movements of said diaphragm, an arm fixed on said shaft, a gear segment support by said arm, a rotatable sleeve carrying the said rotary member, and a gear segment mounted on said sleeve and meshing with the gear segment of the said arm.

5. A search light apparatus, comprising in combination a gas burner, a screen device consisting of a semi-cylindrical fixed member and a semi-cylindrical rotary member, means operated by the gas feeding said burner, whereby the screen is kept out of screening position as long as the light is burning, and a spring for keeping the screen in screening position as long as the light is extinguished.

6. A search light apparatus comprising in combination a gas burner, a screen device consisting of a fixed member and a rotary member, means operated by the gas feeding the burner, whereby the screen is kept out of screening position as long as the light is burning, and a spring for actuating the rotary member of the screen so as to keep it in screening position as long as the light is extinguished.

7. A search light apparatus comprising in combination a gas burner, a screen device comprising a fixed member and a rotary member, an incandescent body carried by said fixed member, a standard for carrying the screen device and means for joining the said fixed member to the standard so as to allow extraction of the incandescent body.

In testimony whereof I have signed my name to this specification in the presence of two subscribing witnesses.

GUSTAF DALEN.
